PADLOCK

Gunnar E. Swanson, Middletown, Conn.

Application December 16, 1954, Serial No. 475,631

6 Claims. (Cl. 70—38)

The invention relates to a padlock and as to some of its aspects it is particularly applicable to a padlock of the character disclosed in my patent entitled Locking and Unlocking Mechanism for Cylinder Locks, No. 2,444,542, dated July 6, 1948.

One object of the invention is to provide a padlock having simple and reliable means for retaining the rotatable cylinder in place in the body, the said means having no exteriorly exposed parts and having a snap action upon assembly of the cylinder with the body.

A further object of the invention is to provide a simplified padlock construction wherein a single spring effects the aforesaid snap action and also serves to bias the cylinder downwardly or rotatively or both.

A further object of the invention is to provide a padlock having simple and reliable means for retaining the shackle in place in the body, the said means having no exposed parts at the side of the body.

Other objects of the invention will be apparent from the drawings and from the following description and claims.

In the drawings I have shown in detail a preferred embodiment of the invention, but it will be understood that various changes may be made from the construction shown, and that the drawings are not to be construed as defining or limiting the scope of the invention, the claims forming a part of this specification being relied upon for that purpose.

Of the drawings:

Fig. 1 is a vertical central sectional view of a padlock embodying the invention with certain parts in intermediate positions of assembly, the shackle being out of its extended position.

Fig. 2 is a view similar to Fig. 1 but showing the parts fully assembled and also including a dotted line showing of the shackle in its locked position.

Fig. 3 is a vertical sectional view taken along the line 3—3 of Fig. 2, but with the cylinder and certain other parts shown in elevation.

Fig. 4 is a horizontal sectional view taken along the lines 4—4 of Figs. 2 and 3.

Fig. 5 is a horizontal sectional view taken along the lines 5—5 of Figs. 2 and 3.

Fig. 6 is a horizontal sectional view taken along the lines 6—6 of Figs. 2 and 3.

Fig. 7 is a face view of the shackle retainer before insertion.

Fig. 8 is a left edge view of the retainer shown in Fig. 7.

Fig. 9 is a top view of the retainer shown in Figs. 7 and 8.

Fig. 10 is a view similar to Fig. 7 but showing an alternative shackle retainer.

Fig. 11 is a left edge view of the retainer shown in Fig. 10.

Fig. 12 is a view similar to Fig. 2 but showing the

2

cylinder in elevation and turned to unlock the shackle and showing the shackle in its unlocked position.

Fig. 13 is a vertical sectional view taken along the line 13—13 of Fig. 12, the cylinder being shown in elevation.

Fig. 14 is a horizontal sectional view taken along the line 14—14 of Fig. 12.

Fig. 15 is a horizontal sectional view taken along the line 15—15 of Fig. 12.

Fig. 16 is a horizontal sectional view taken along the line 16—16 of Fig. 12.

Fig. 17 is a view similar to Fig. 15 but showing some of the parts in different positions.

Fig. 18 is a view similar to Fig. 16 but showing some of the parts in the same positions as in Fig. 17.

Fig. 19 is a view somewhat similar to Fig. 14 but showing the cylinder and the shackle in their locked positions, this view being taken along the line 19—19 of Fig. 2 except that the shackle is shown in its locked position.

Referring to the drawings and more particularly to Figs. 1 to 6 thereof, 10 is the body of a padlock embodying the invention. The body may advantageously be a unitary one-piece die casting, and with one exception

all portions thereof are preformed during the casting operation. Said body has a preformed vertical generally cylindrical recess 12 for a cylinder, this recess being open at the bottom and partly closed at the top, and said body has a preformed vertical hole 14 for a shackle, this hole being open at the top and substantially closed at the bottom. The body 10 has been referred to as being in vertical position and for convenience of description such terms as "vertical" and "horizontal" will be used in describing other parts. These terms are intended to merely designate the relationship of parts and not to limit the scope of the invention.

A cylinder 16 is rotatable in the recess 12, the cylinder being retained in place and effecting its functions by means of associated parts to be more fully described.

40 A U-shaped shackle 13 is provided which is hinged and also vertically movable. Said shackle has its hinge leg 20 entered in the hole 14, the locking leg 22 of the shackle being adapted to enter a hole 24 which is in the top of the body and which communicates with the cylinder recess 12. The said locking leg of the shackle has a notch 26 for receiving a portion of the cylinder 16 so as to be locked thereby as hereinafter explained. A shackle spring 28 of conventional form is provided between the end of the shackle leg and the bottom of the hole 14. The hinge leg 20 of the shackle has an annular recess which provides an annular shoulder 30. In Fig. 1 the shackle is shown somewhat below its fully extended position, and in Fig. 2 it is shown by full lines in its fully extended unlocked position and by dotted lines in its locked position.

Relative upward movement of the cylinder 16 in the recess 12 may be limited either by the top wall of the body or by a flange 32 near the bottom of the cylinder or by both. The flange 32 enters a preformed countersink 33 in the body 10. Relative rotative movement of the cylinder 16 is limited by a thicker portion 34 of the flange 32 which enters a preformed arcuate recess 36 in the body. Fig. 4 shows the portion 34 in the recess 36, the cylinder being in its locked position. The cylinder is turned counterclockwise from the Fig. 4 position to its unlocked position. The countersink 33 and the recess 36 in the body are sufficiently deep to permit limited upward movement of the cylinder beyond the normal level shown in Figs. 2 and 3.

70 The cylinder 16 is provided with a conventional key slot 37 and with conventional transversely movable spring

pressed tumblers 38, 38, one of which is clearly shown in Fig. 5. When the cylinder is in locked position as shown in Figs. 2 to 6, the tumblers 38, 38 extend to varying extents into a vertical locking groove 40 in the cylinder recess 12. A groove 42 is preferably provided opposite the groove 40. When the cylinder is in unlocked position as shown in Fig. 15, the tumblers extend into a vertical groove 44 in the cylinder opening 12. A groove 46 is preferably provided opposite the groove 44. The grooves 44 and 46 have inclined side faces as shown in Fig. 15, so that the tumblers are cammed inwardly upon clockwise turning of the cylinder from its unlocked position toward its locked position. All of said grooves 40, 42, 44 and 46 are preformed. The before-mentioned flange 32 at or near the bottom of the cylinder serves as a guard to prevent access to the tumblers from the bottom of the lock.

For retaining the cylinder 16 so as to prevent downward movement thereof and for other purposes, there is provided a cylinder retainer 48 which is carried by the cylinder above the bottom thereof and which is movable relatively thereto between an inner position and an outer position. Preferably and as shown, the retainer 48 is radially slideable in a radial slot 50 formed in said cylinder 16. For a purpose to be stated, the retainer preferably has a finger 52 provided with an inner face which is inclined upwardly and outwardly at a suitable angle which is shown as being about 45°. The cylinder recess 12 is provided with a circumferentially extending arcuate undercut or groove 54 which is at such a level that it can receive a portion of the retainer 48 when the cylinder is fully entered in the recess 12 in the body and when the retainer is moved to its outer position. The slot 54 cannot be readily preformed in the die casting of the body, and it is preferably a kerf formed by a milling or sawing operation after the body is otherwise complete. The groove or kerf 54 may extend entirely around the recess 12, but it is ordinarily sufficient for it to extend about as shown in Fig. 6.

A spring is provided which is positioned for biasing the retainer outwardly toward its said outer position and for holding it in the last said position. The spring may be widely varied but it is preferably a coil spring 56 having other functions to be described. As shown, said spring 56 is located between the cylinder 16 and the wall of the body at the top of the recess 12, the spring being compressed so that it applies downward pressure. This spring throughout most of its length is within a vertical opening in the cylinder and it is therefore supported against lateral movement. In assembling the cylinder and its associated parts relatively to the body 10, the parts are preliminarily assembled as shown in Fig. 1, retainer engages and partly compresses the spring 56, and by reason of the inclination of said finger the retainer is biased for outward movement. The retainer cannot actually move outwardly until it comes into register with the groove or kerf 54, this occurring when the cylinder is at a normal or pre-established level with respect to the body. It then moves or snaps into said groove or kerf 54 as shown in Fig. 2, and it restricts downward movement of the cylinder. The spring 56 normally prevents the retainer 48 being below the groove or kerf 54 and therefore not entered therein. The finger 52 on the retainer prevents any subsequent inward movement of the retainer and therefore holds said retainer in its operative position. The groove or kerf 54 has sufficient vertical thickness to permit limited movement of the cylinder and the retainer upwardly from the normal or pre-established level shown in Fig. 2.

The spring 56 not only holds the retainer 48 in its outer operative position, but it also presses the cylinder and the retainer downwardly and resists upward movement thereof above the normal level. The retainer 48 has a downwardly bowed portion 58 which is shaped to provide a depending detent, and the groove or kerf 54 is

formed at the bottom thereof with two detent spaces 60 and 62 each adapted to partly receive said detent. For convenience of die-casting, spaces 60 and 62 are preferably preformed vertical slots extending upwardly from the slots 40 and 44 and terminating at the horizontal kerf 54. When the detent spaces 60 and 62 are formed by preformed vertical slots terminating at the kerf 54 which is machined, it is possible to preform the complete body by die-casting without any machining operation other than that for the kerf 54.

With the detent 58 held in the space 60 by the action of the spring as shown in Figs. 2 and 6, the retainer tends to hold the cylinder in its locked position. With the detent held in the space 62 by the action of the spring as shown in Figs. 13 and 16, the retainer tends to hold the cylinder in its unlocked position. In unlocking, the key must withdraw the tumblers and it must also apply sufficient force to the cylinder to turn it, the cylinder and retainer moving slightly upwardly as the detent 58 is forced out of the space 60. Turning is continued until the detent 58 enters the space 62 when the cylinder and retainer move slightly downwardly.

The spring 56 has a third function which is to bias the cylinder for rotative movement in the clockwise direction. The spring has an upper lateral extension 64 which engages a boss 66 on the body as shown in Fig. 2 and it has a lower lateral extension 68 which is entered in a slot 70 in the cylinder as shown in Fig. 6. While the spring biases the cylinder for clockwise movement, the flange portion 34 shown in Fig. 4 prevents such movement beyond the locked position. When the cylinder is in the unlocked position, clockwise movement is resisted by the engagement of the detent 58 with the edges of the space 62.

The cylinder 16 is provided with a ledge 72 which is adapted to enter the notch 26 in the shackle leg 22 when said leg is in its lower position within the hole 24 and when the cylinder is turned into its locked position. In order that the cylinder may be turned into its locked position without the use of a key, said cylinder is provided with an inclined face 74 which is engageable by the locking leg 22 of the shackle as the shackle is moved downwardly, the said face 74 being shown in Figs. 12, 13 and 14. Said Fig. 14 shows the relationship of the inclined face 74 to the hole 24 through which the shackle leg 22 enters the body. Figs. 15 and 16 are similar respectively to Figs. 5 and 6, but show the various parts in unlocked positions. It will be clear from Fig. 16 that the detent 58 is holding the parts in their unlocked positions, said detent overcoming the bias of the spring 56.

As the shackle is moved downwardly to its locked position as shown by dotted lines in Fig. 2, the inclined face 74 forces the cylinder to turn in the clockwise direction, the parts being moved to positions such as those shown in Figs. 17 and 18. In these positions the detent 58 is out of the space 62 and the tumblers 38 have been cammed inwardly. The cylinder and its associated parts are therefore free to be moved additionally in the clockwise direction by the spring 56 to their locked positions. Figs. 2, 4, 5, 6 and 19 show the cylinder and its associated parts and also the shackle in their locked positions, the locked position of the shackle being shown in Fig. 2 by dotted lines. The tumblers 38 have entered the groove 40 to hold the cylinder in locked position and the ledge 72 of the cylinder has entered the notch 26 of the shackle to hold it in locked position. Actually, the shackle may be moved downwardly somewhat below the position shown by dotted lines in Fig. 2, the movement being limited by the stop face 75 on the body. With the leg 22 of the shackle engaging the face 75, the ledge 72 can freely move into the notch 26.

The action of the retainer 48 for holding the cylinder has been fully described. It is sometimes necessary to remove the cylinder from the body after it has been assembled therewith, removal being required for repair, or

for adjustment or for key changes. With the cylinder and associated parts in the positions shown in Fig. 2 and with the shackle swung out of the way, a tool may be inserted through the hole 24 to move the retainer 48 toward its inner position. This withdraws the retainer from the groove or kerf 54 and permits the cylinder to be pushed downwardly by the spring 56. The stated possibility for cylinder removal does not interfere with the security provided by the lock, as the retainer 48 is completely inaccessible when the shackle is in its locked position.

It will be observed that a padlock embodying the present invention has considerable similarity to that disclosed in my said patent. The present invention, so far as it involves the cylinder and the parts directly associated therewith, relates more particularly to the retainer 48 and to the parts with which it engages. The retainer and its associated parts act automatically to hold or retain the cylinder as soon as it is fully assembled with the body. The cylinder is reliably held but there are no externally exposed parts.

The shackle and the functioning thereof have been fully described, but no mention has been made of the means for connecting the shackle with the body 10. This means is set forth and claimed in my copending application, Serial No. 520,261, filed July 6, 1955, as a division of this present application.

A shackle retainer 76 is provided which is shaped and adapted to fit the hereinafter described slot in the body 10. As shown in Figs. 7, 8 and 9, this retainer is a vertical metal plate having in horizontal section flat side sections 78, 78 and a central section 80 which is bowed toward the left. Short vertical slots 82, 82 near the top separate the central section from the edge sections. Preferably at least one of said side sections 78, 78 is provided near its bottom with a small bulge 83 which projects transversely toward the right as shown in Fig. 8. As shown, both side sections are provided with the described bulges which are somewhat exaggerated for convenience of illustration. The central section 80 of the retainer 76 is provided at the front with a groove or depression 84 which extends transversely at a position near the bottoms of the slots 82, 82. The depression 84 weakens the said central section for assuring correct bending as hereinafter explained. The central section 80 of the retainer 76 is also provided above the bottom thereof with a resilient tongue 85 attached only at its top and biased laterally toward the right as shown in Fig. 8.

As shown in Figs. 4, 5 and 6 the body is provided with a generally vertical slot 86 which extends upwardly from the bottom of the body and which is closely adjacent the shackle hole 14. In horizontal section the slot 86 has the same shape as the retainer 76, the slot being so located that a retainer in the slot will have the concave side of its bowed central section substantially coincident with the periphery of said hole 14. The slot and the hole are in communication at said concave side of the bowed portion of the former. Said slot 86 has its central section near its upper end provided with a transversely inclined sweep so that said section terminates in said hole 14, said transversely inclined portion being shown at 88 in Figs. 1 and 2. The slot 86 has the top of its side sections spaced from the bottom of the body by a distance equal to or slightly exceeding the length of the retainer 76. The inclined central portion of the slot is spaced from the bottom of the body by a distance less than the length of the retainer. The flat side sections of the slot extend above the level where the central section terminates in the hole.

For assembly, the shackle is positioned as shown in Fig. 1, or in any position below its fully extended position. Then the retainer 76 is entered in the slot 86 and driven upwardly therein. Fig. 1 shows the retainer in an intermediate position. When the retainer is driven above the Fig. 1 position, side sections 78, 78 remain straight but the inclined portion 88 of the slot engages

the central section 80 of the retainer to deflect or bend it toward the right and into the hole 14, as shown in Fig. 2. The groove or depression 84 in the retainer facilitates the described proper bending thereof by the inclined portion 88 of the slot. The flat side sections 78, 78 of the retainer extend above the level where the central section 80 enters said hole 14. The portion 80 of the retainer, deflected into the hole 14 as described, is above the shoulder 30 of the shackle, thus limiting upward movement of the shackle.

As the retainer is driven into the slot the bulges 83 are flattened, thus providing frictional resistance that tends to prevent downward movement of the retainer. It will be understood that said bulges are somewhat exaggerated in the drawing. The tongue 85, when provided, is initially flexed toward the left from the position shown in Fig. 1, and it then snaps toward the right and into the hole 14 as shown in Fig. 2 so as to engage the bottom of said hole and thus prevent relative downward movement.

Figs. 10 and 11 show a retainer 90 that can be used as an alternative to the retainer 76. The retainer 90 differs in the omission of the groove or depression 84 and of the tongue 85 which may not always be necessary.

The invention claimed is:

1. In a padlock, the combination of a body having a generally cylindrical vertical recess open at the bottom and also partly open at the top for receiving the locking leg of a shackle which recess is provided at one side with a vertical locking groove and is provided above its bottom with a circumferentially extending horizontal retaining groove, a cylinder rotatably movable in the recess between locked and unlocked positions, key controlled tumblers on the cylinder positioned to enter said locking groove for locking the cylinder in said locked position, means on said cylinder for engaging the locking leg of a shackle when the cylinder is in locked position, a retainer carried by said cylinder and movable relatively thereto between an inner position and an outer position wherein an outer portion of said retainer projects beyond the cylinder, said retainer having a portion with an inner face which is inclined upwardly and outwardly and said retainer being so spaced from the bottom of the cylinder that its last said portion can project into said retaining groove when the cylinder is at a pre-established level in the recess, and a vertical coil spring positioned above the retainer and applying downward pressure which spring is so located that when the retainer is in its inner position said inclined face on said retainer engages one side of the spring with the result that downward pressure applied by the spring serves to bias the retainer for outward movement into the retaining groove where it is then confined so as to restrict downward movement of the cylinder while permitting rotative movement thereof.

2. In a padlock, the combination of a die-cast body having a preformed generally cylindrical vertical recess open at the bottom and also partly open at the top for receiving the locking leg of a shackle which recess is provided at one side with a preformed vertical locking groove and is also provided at one side with a preformed vertical groove extending upwardly above the level of the top of said locking groove, a cylinder rotatably movable in the recess between locked and unlocked positions, said cylinder being provided with a circumferentially extending kerf above the locking groove and intersecting the second said vertical groove so that the last said groove provides a detent space in the bottom of the kerf, a cylinder rotatably movable in the recess between locked and unlocked positions, key controlled tumblers on the cylinder positioned to enter said locking groove for locking the cylinder in said locked position, means on said cylinder for engaging the locking leg of a shackle when the cylinder is in locked position, a retainer carried by said

cylinder and spring biased for relative movement from an inner position to an outer position wherein a portion of said retainer projects beyond the cylinder and into said kerf, said retainer being so spaced from the bottom of the cylinder that its last said portion can project into said kerf when the cylinder is at a pre-established level in the recess and said projecting portion of the retainer having a detent located to enter the detent space in said kerf when the cylinder is in a predetermined rotative position, and a spring for biasing the cylinder and the retainer downwardly so that the detent of the retainer when entered in said detent space resists rotation of the cylinder.

3. In a padlock, the combination of a body having a generally cylindrical vertical recess open at the bottom and also partly open at the top for receiving the locking leg of a shackle which recess is provided at one side with a vertical locking groove and is provided above its bottom with a circumferentially extending horizontal retaining groove having a detent space in the bottom thereof, a cylinder rotatably movable in the recess between locked and unlocked positions, key controlled tumblers on the cylinder positioned to enter said locking groove for locking the cylinder in said locked position, means on said cylinder for engaging the locking leg of a shackle when the cylinder is in locked position, a retainer carried by said cylinder and movable relatively thereto between an inner position and an outer position wherein a portion of said retainer projects beyond the cylinder, said retainer being so spaced from the bottom of the cylinder that its last said portion can project into said retaining groove when the cylinder is at a pre-established level in the recess and said projecting portion of the retainer having a detent located to enter said detent space in the retaining groove when the cylinder is in a predetermined rotative position, a vertical coil spring applying downward pressure thereto so that the retainer when in its outer position is biased downwardly to enable its detent to resist rotation of the cylinder, and means causing said spring to also bias the retainer outwardly toward its said outer position and to hold it in its last said position whereby upon upward movement of the cylinder and retainer within the recess during assembly said portion of the retainer is snapped into the retaining groove and is then confined therein to restrict downward movement of the cylinder while permitting rotative movement thereof.

4. In a padlock, the combination of a body having a generally cylindrical vertical recess open at the bottom and also partly open at the top for receiving the locking leg of a shackle which recess is provided at one side with a vertical locking groove and is provided above its bottom with a circumferentially extending horizontal retaining groove, a cylinder rotatably movable in the recess between locked and unlocked positions, key controlled tumblers on the cylinder positioned to enter said locking groove for locking the cylinder in said locked position, means on said cylinder for engaging the locking leg of a shackle when the cylinder is in locked position, a retainer carried by said cylinder and movable relatively thereto between an inner position and an outer position wherein a portion of said retainer projects beyond the cylinder, said retainer being so spaced from the bottom of the cylinder that its last said portion can project into said retaining groove when the cylinder is at a pre-established level in the recess, a vertical coil spring engaging the body and the cylinder for biasing the latter for rotative movement, and means causing said spring to also bias the retainer outwardly toward its said outer position and to hold it in its last said position whereby upon upward movement of the cylinder and retainer within the recess during assembly said portion of the retainer is snapped into the retaining groove and is then confined therein to restrict downward movement of the cylinder while permitting rotative movement thereof.

5. In a padlock, the combination of a body having a

generally cylindrical vertical recess open at the bottom and also partly open at the top for receiving the locking leg of a shackle which recess is provided at one side with a vertical locking groove and is provided above its bottom with a circumferentially extending horizontal retaining groove having a detent space in bottom thereof, a cylinder rotatably movable in the recess between locked and unlocked positions, key controlled tumblers on the cylinder positioned to enter said locking groove for locking the cylinder in said locked position, means on said cylinder for engaging the locking leg of a shackle when the cylinder is in locked position, a retainer carried by said cylinder and movable relatively thereto between an inner position and an outer position wherein a portion of said retainer projects beyond the cylinder, said retainer being so spaced from the bottom of the cylinder that its last said portion can project into said retaining groove when the cylinder is at a pre-established level in the recess and said projecting portion of the retainer having a detent located to enter the detent space in the retaining groove when the cylinder is in a predetermined rotative position, a vertical coil spring engaging the body and the cylinder for biasing the cylinder for rotative movement, said spring also engaging said cylinder to apply downward pressure thereto so that the retainer when in its outer position is biased downwardly to enable its detent to resist rotative movement of the cylinder by said spring, and means causing said spring to also bias the retainer outwardly toward its said outer position and to hold it in its last said position whereby upon upward movement of the cylinder and retainer within the recess during assembly said portion of the retainer is snapped into the retaining groove and is then confined therein to restrict downward movement of the cylinder while permitting rotative movement thereof.

6. In a padlock, the combination of a body having a generally cylindrical vertical recess open at the bottom and also partly open at the top for receiving the locking leg of a shackle which recess is provided at one side with a vertical locking groove and is provided above its bottom with a circumferentially extending horizontal retaining groove having a detent space in the bottom thereof, a cylinder rotatably movable in the recess between locked and unlocked positions, said cylinder having a cam face engageable by the leg of said shackle upon downward movement of the latter for rotatably moving said cylinder from its unlocked position toward its locked position, key controlled tumblers on the cylinder positioned to enter said locking groove for locking the cylinder in said locked position, means on said cylinder for engaging the locking leg of said shackle when the cylinder is in locked position, a retainer carried by said cylinder and movable relatively thereto between an inner position and an outer position wherein a portion of said retainer projects beyond the cylinder, said retainer being so spaced from the bottom of the cylinder that its last said portion can project into said retaining groove when the cylinder is at a pre-established level in the recess and said projecting portion of the retainer having a detent located to enter said detent space in the retaining groove when the cylinder is in its unlocked position, a vertical coil spring engaging the body and the cylinder for biasing the cylinder for rotative movement from its unlocked position to its locked position, said spring also engaging said cylinder to apply downward pressure thereto so that the retainer when in its outer position is biased downwardly to enable its detent to resist rotative movement of said cylinder by said spring, and means causing the spring to also bias the retainer outwardly toward its said outer position and to hold it in its last said position whereby upon upward movement of the cylinder and retainer within the recess during assembly said portion of the retainer is snapped into the retaining

groove and is then confined therein to restrict downward movement of the cylinder while permitting rotative movement thereof.
